PAGE 2

Fig 3

Fig 4

Figure 1 is a perspective view of a marine running light, showing my new design;

Figure 2 is a side elevation view thereof;

Figure 3 is a front elevational view thereof; and

Figure 4 is a top plan view thereof.

This application is a continuation-in-part of my earlier application Serial No. D. 41,876, filed June 12, 1956, now abandoned.

I claim:

The ornamental design for a marine running light, as shown.
